(57) **CLAIM**

The ornamental design for a lid for container, as shown and described.

DESCRIPTION

FIG. 1 is a top view of a lid for container showing our new design;

FIG. 2 is a bottom view thereof;

FIG. 3 is a right side view thereof, the left side view being a mirror image;

FIG. 4 is a front view thereof;

FIG. 5 is a rear view thereof;

FIG. 6 is a top view of the lid for container, with the lid in an open position of use;

FIG. 7 is a bottom view thereof;

FIG. 8 is a right side view thereof, the left side view being a mirror image thereof;

FIG. 9 is a front view thereof; and,

FIG. 10 is a rear view thereof.

The broken lines are shown for the purpose of illustrating parts of the article that form no part of the claimed design. The drawings include surface shading which illustrates contour and not surface ornamentation.

1 Claim, 10 Drawing Sheets
